(57) CLAIM

We claim the ornamental design for a sanitizing machine with the top door open, as shown and described.

DESCRIPTION

FIG. 1 is a perspective view of a sanitizing machine, showing the new design;

FIG. 2 is a front view of a sanitizing machine thereof;

FIG. 3 is a back view of a sanitizing machine thereof;

FIG. 4 is a side view of a sanitizing machine thereof;

FIG. 5 is a side view of a sanitizing machine thereof;

FIG. 6 is a top plan view of a sanitizing machine thereof; and,

FIG. 7 is a bottom view of a sanitizing machine thereof.

The broken lines in the drawing views are included for the purpose of illustrating portions of the sanitizing machine with top door open that form no part of the claimed design.
